WILLIAM A. KONEMAN AND HIRAM H. SCOVILLE, OF CHICAGO, ILLINOIS;
SAID SCOVILLE ASSIGNOR TO AZEL F. HATCH, OF SAME PLACE.

ORE-CONCENTRATOR.

SPECIFICATION forming part of Letters Patent No. 315,147, dated April 7, 1885.

Application filed July 25, 1884. (No model.)

To all whom it may concern:

Be it known that we, WILLIAM A. KONEMAN and HIRAM H. SCOVILLE, of Chicago, county of Cook, State of Illinois, have invented 5 certain new and useful Improvements in Endless-Belt Ore Concentrating or Vanning Machines; and that we hereby declare the following to be a true and correct description of the same.

Heretofore in vanning-machines the materials have been agitated while partly suspended in flowing water. This agitation has been confined to end or side shake of the vanning-surface over which the mixture of ore and 15 gangue was deposited.

According to physical laws, shaking in substantially horizontal directions tends to settle and stratify the material according to specific gravities, but will not so separate them that 20 the material of one gravity may readily pass off in one direction, and material of another gravity pass off in another direction; but such complete separation is required of a vanning-machine, because the ore is expected to discharge over one side or end of the table while 25 the sand passes over the opposite side or end.

To obviate the effect of settling in preventing a complete separation according to gravities, we have given to the vanning-surface a 30 vertical shake, whereby the tendency to settle is counteracted and the stratification according to gravity is facilitated. The effect of the vertical shake is enhanced by making the upward movement at a different speed from the 35 downward movement.

Another physical law is made available to facilitate the complete separation of the materials, and that is the law which causes bodies in contact to adhere. Thus when the vanning- 40 surface is caused to fall in vertical plane the material which is in contact with said surface will be affected more than that which is immersed in the mobile fluid above, and the heavier material will be affected more than 45 the lighter material.

It is well known that the difference in specific gravity between the ore and its gangue varies greatly, and it is plain that the maximum effect of agitation will be attained when 50 the quantity and speed of the agitation are

delicately adjusted to the particular ore under treatment.

The object of our improvements is to produce an apparatus or machine for the purpose of ore-concentration so adjustable in all its 55 motions—namely, length of stroke or oscillation, speed of stroke or oscillation, height of lift and sudden drop, speed of belt-travel, and inclination of belt—as to meet such conditions and requirements of metal-bearing ores as are 60 due to the great difference in specific gravity between the metallic portion and the gangue, as well as on account of the greater or less degree to which such ores are oxidized or decomposed, and the quantity of metal contained in 65 them having a tendency to float in a water current; also, to enable the regulation of motion and speed to meet the different requirements in an ore owing to the difference in fineness to which it has been reduced. 70

In the following specification, and in the drawings attached thereto, we have set out the employment of a revolving cam to produce the gradual lift and sudden drop of the vanning-surface; but it is evident that this result 75 may be produced by a cam located differently from that shown, or by a stationary cam-track, or by other known mechanical expedients. In the same way the fulcrums of the arms which vibrate the vanning-surface are shown 80 with adjusting-screws; but it is evident that said fulcrums may be adjusted by means of wedges and other known devices.

We have employed a crank to produce the horizontal vibration of the vanning-surface; 85 but the same vibration has been produced by cranks arranged in various ways, and by cams; therefore we do not desire to be limited to these particular devices, as shown herein.

Referring to the drawings, which are part 90 and parcel of this specification, Figure 1 represents a side elevation of our apparatus. Fig. 2 represents a longitudinal section. Fig. 3 represents a downward plan or view. Fig. 4 represents a longitudinal section through 95 the slide on the radial arm. Fig. 5 represents an enlarged view of cam and stirrup, its connection with the radial arm and radial arm-belt. Fig. 6 represents a view of belt-regulating adjustment. Fig. 7 represents a sec- 100

tion through frame and guide, showing sliding adjustment of box *i* at the tail end of machine. Figs. 8 and 9 are detail elevations of mounting and driving gear for belt-wipers. Figs. 5 10 and 11 are section and elevation of vibrating-arm mounting. Fig. 12 is a perspective of crank and cam. Fig. 13 is a series of diagrams of the movements of the table.

A represents the frame of the machine.

10 *B* represents the carrier-frame suspended from the top of the frame *A* by rods or cords *a*, so that it may swing or oscillate.

E is a drum at the head of the carrier-frame, journaled in boxes *E'*, attached to the frame *B*. 15 The caps of said boxes extend downward, and each forms two arms, *a'* *a''*, which form boxes for the journals of the wiping-rolls *x x*.

X is a box to receive the concentrates that are wiped off the belt by wiping-rolls *x x*.

20 *J* is a worm-wheel on the axle of the drum *E*, driven by a worm, *j*.

J' is a sprocket or chain wheel on the same axle, around which a chain, *c'*, passes, and thence down around a similar wheel on each 25 of the wiping-roll shafts, which revolve the wiping-rolls coincidently with the belt travel.

G is a drum at the tail of the frame, journaled in a sliding adjustable box, *i*, on each side of the frame *B*. These boxes are planed 30 and fitted to grooved ways *H* in frame, as shown in Fig. 7, and are thrust out or drawn in to put the proper tension on the traveling belt by screws *h*³ *h*³, simultaneously operated by means of a socket-wrench on a transverse

35 shaft, *i*, which carries the bevel or miter wheels *h' h'*. These wheels are fastened to the shaft *i'* by set-screws, instead of keys, in order that either end of the drum may be adjusted without moving the other end to compensate for 40 uneven stretch of the belt.

D is a wide endless belt passing around drums *E G*, and supported intermediately by rollers *g g*, whose bearings are in the frame *B*, and is given constant motion around said 45 drums by means of the worm *j*, which itself is given any speed required by the cone-pulleys *V V'*, their belt *V²*, and chain-wheel *v* on the shaft of cone-pulley *V'* and chain-wheel *v'* on the worm *j*, around which passes chain *v²*.

50 Motion is given the upper cone-pulley, *V*, by the bevel or miter wheels *K' K²* from the main driving-shaft *k* and pulley *K*. The shaft *k* also carries a cone-pulley, *L*, from which a belt, *L'*, drives the cam and crank shaft *l*, upon 55 which is cone-pulley *M*, corresponding to cone-pulley *L*.

Upon the extreme ends of the shaft *l* are cranks *P*, and immediately inside the frame *A*, upon which the shaft is journaled, is the 60 cam *N*, and between cam *N* and cone-pulley *M* a balance-wheel, *r*, is keyed to shaft *l*, to impart steadiness to the motion. Around cam *N* is a yoke, *O*, which is held in position by bearings *m m* on the frame *A*.

65 To one end of yoke *O* a connecting-rod, *T*, is attached, and the other end of connecting-rod *T* is pivoted on the link-block *S'*, which is

fitted in the radial arm *S* and raised, lowered, or held in position required at will by the screw *s*, rotated by bevel or miter wheels *s' s''*, operated by chain-wheel *t*, and chain *t'*, running down around a sprocket, *t''*, on shaft *u'*, which the operator turns by hand when he desires to raise or lower the link-block *S'* in the radial arm to regulate the rise and drop of the head 75 of the carrier-frame *B*.

In order that the position of the link-block *S'* may be shifted without changing the angular position of the arm *S* at the moment, we provide said arm with a longitudinal slot 80 curved on a radius equal to the length between centers of the connecting-rod *T*; and in order to permit said block to be longitudinally adjustable by means of the screw *s* we fit to said curved slot a slide, *S''*, and provide the block 85 *S'* with a cylindrical joint-pin, *s''*, which passes through said slide, and is adapted at its extremity to form the pivot for the connecting-rod joint. The screw *s* passes through said block *S'*, and at its extremity it revolves in a bearing, *S''*, which has a pivotal connection with the arm *S*, and also supports the bearing for the bevel-wheel *s''* and sprocket *t*.

P P are cranks on the ends of shaft *l*, to which are attached connecting-rods *n n*, the other ends of said rods *n n* being attached to the upper ends of vibrating levers *R R*, which are fulcrumed on movable blocks *R''*, and at their lower ends pivoted to the carrier-frame *B*.

y'' is a shaft central with levers *R* and journaled upon frame *A*. This shaft has upon its extreme ends bevel or miter wheels *y'*, meshing into bevel or miter wheels *y* on the end of screws *R'*, which raise and lower the pivotal boxes *R''* in levers *R* when the screws are rotated, which is accomplished by a chain, *c'*, passing over chain-wheel *c''* and thence down to within easy reach of the operator, where it passes round a similar chain wheel, *c''*, on a shaft, *c''*, which is turned by the assistant to 110 revolve the screws *R'* and raise or lower the pivotal blocks *R''* in the levers *R R*, as desired, to give more or less vibration to the carrier-frame *B*.

t'' is an idler-chain passing over the idler-chain wheel *t''*, journaled on the shaft *u'*, and the chain-wheel *t''* on the shaft *u''*, to keep the chain *t'* always of proper length during changes of position of said arm. *u'* is a shaft journaled on frame *A*, and provided with the radial arm *S* and the counterbalancing-arm *b''*, upon which is counter-weight *W*, and the arms *U U*, from the extremities of which the head of the carrier-frame *B* is suspended by means of the rods or cords *a*, which are attached to the carrier-frame *B* by brackets *b*. These ropes are provided with turn-buckles *b''*, to keep the carrier-frame in perfect level transversely.

p p are bracket-bearings fastened to both 120 sides of carrier-frame *B*, and the lower ends of the vibrating arms *R R* are journaled on them.

B'' is a distributing or spreading box for

the ore to be concentrated. Z is a tailings box or sluice. The rear end of the frame B does not have any lift and drop in its operation; therefore the rear end of said frame is supported by cords a' , the upper ends whereof are wound upon drums d on the shaft e ; but the rear end of said frame may be raised or lowered to adjust the frame B and its belt D as to pitch toward the tail by turning said shaft. This may be accomplished at will by means of a chain, e^2 , which passes over a sprocket-wheel, e^3 , on said shaft e and under a similar wheel on the shaft e^4 . The shaft e is also provided with a counter-balancing arm, 15 e^5 , and weight W' , adjustable thereon, so that the carrier may be easily raised or lowered. The shafts c^6 , u^7 , and e^8 are each provided with ratchets f and pawls f' , whereby they may be prevented from revolving, except when required by the operator; but adjustments may be changed as required without stopping the machine.

The operation of the machine, one of which we now have in successful use, demonstrating 25 all parts as herein set forth, is as follows: The ore to be operated upon, after first having been pulverized to a suitable degree of fineness—say from forty to eighty mesh—by any proper method of pulverization, is fed onto 30 the revolving belt D by means of a suitable distributer, B^2 , at a point varying from two to four feet distant from the drum E or head of the table. Sufficient water is introduced with the ore to cause the same to flow quite freely, 35 and fresh water is distributed on the table through a finely-perforated pipe, F, at a point about one foot distant from—that is to say, higher up and toward the head of the table than—the point at which the ore is being distributed. It is now necessary to find the exact motion under which the ore will give the 40 cleanest concentrates. The stroke oscillation of the frame B can be varied from one-half inch to four inches by raising or lowering 45 pivoting slides R^2 on screw R' , as described. The finer the ore and the more completely decomposed it is the less the stroke and the greater the speed of stroke required. The speed is regulated by shifting the position of 50 the belt L' on the cone-pulleys M L. The height of the lift and drop affording the best results is now tested. It varies from five-eighths of an inch to one and one-quarter of an inch, the same rule holding good as with 55 the stroke—the finer and more decomposed the ore the less the lift and drop. It is necessary to describe the action of the table on ores by this combination of a slow forward stroke with an upward lift at the same ratio of speed, 60 together with a quick backward stroke and a sharp drop of the forward or higher end of the frame. The result is a triangular motion or movement at any certain point on the belt, varying in shape with the adjustment of 65 the frame. As illustrations, three combinations are shown in Fig. 13, wherein are diagrams of the various combinations of motion

of the swinging table and belt, 1 representing the extreme with a long stroke and a short lift, 2 a short stroke and high lift, 3 the shortest stroke and shortest lift combined, and the remainder illustrate other combinations of motions. The action of this motion on the ore is that the belt on traveling forward or toward its head—that is, from 4 to 5—is lifted toward 70 5 by the cam N and the head of the frame B, and the belt is consequently lifted at each stroke toward and up to the floating material, giving all metal in this material an increased movement toward the belt and a chance to adhere and cling to its surface. This upward movement decreases toward the tail end of the frame B and belt D to a radial movement only, so that its action becomes gentler toward the point of its tailing or refuse escape. When 75 the movement is at its highest point—that is, at 5—the frame at the upper end makes a quick drop on account of the escape of the yoke from the cam N, causing a quick backward or downward movement of arms U. This drop of 80 frame causes the sand to be thoroughly separated from the metal, and causes it to be thrown or raised into the current of water, while the metallic portions, on account of greater specific gravity, but principally on account of their 85 tendency to cling to a smooth surface, are only slightly released from the belt and are not raised into the water-current. Their release is sufficient, however, to cause them to travel forward on the belt-surface independent of any 90 belt travel. This independent forward travel is due to the greater speed of belt travel on the back stroke. The distance of 4 5 represents the hypotenuse on the upstroke, and the distance 5 6 4 on the back or downstroke. 95 The gangue-tailings travel downward and wash off over drum G. The concentrates travel upward and off the belt over drum E, and are brushed or scraped into box X by means of belt-wipers x x. The belt speed is regulated by means of cone-pulleys V V', thereby 100 regulating speed of worm j and worm-wheel J. 105

We claim as new—

1. In an ore-concentrator or vanning-machine, a vanning-surface vibrating in a horizontal plane, combined with a cam and operative mechanism adapted coincidentally with said vibration to lift said surface gradually and drop it suddenly, whereby each point of said vanning-surface is caused to describe a 115 triangular path, as described.

2. In an ore-concentrator or vanning-machine, a vanning-surface provided with mechanism adapted to vibrate said surface in a horizontal plane, a cam and operative mechanism to coincidentally lift said surface gradually and drop it suddenly, combined with adjusting-screw and its adjuncts, whereby said horizontal and vertical vibrations may be altered, regulated, and controlled while the machine is 120 running.

3. The combination, in an ore-concentrator or vanning-machine, of a vanning-surface horizontal transversely, but higher at one end than

at the other, a cam and operative mechanism, whereby said surface may be coincidently vibrated horizontally and vertically, the upward and downward movements being made 5 different in speed and direction, as described, and sluices for delivering upon said surface the pulverized ore and gangue and water, whereby said pulverized ore and gangue are subjected simultaneously to both horizontal and 10 vertical vibrations in the presence of a thin sheet of running water.

4. In an ore-concentrator or vanning-machine, a swinging frame set higher at one end than at the other, and a crank and operative 15 mechanism to control the horizontal swing or vibration of said frame, combined with a cam and operative mechanism to cause the higher end of said frame to be lifted gradually and dropped suddenly, for the purpose set forth.

20 5. The combination, in a vanning-machine, of a swinging frame set level transversely, but lower at one end than the other, and an endless belt mounted thereon, having its upper 25 surface moving toward the higher end of the frame, with vibrating levers to cause said frame to swing, and a cam connected with the higher end of said frame to periodically cause it to rise gradually and drop suddenly, whereby the mineral matters having different specific 30 gravities upon the surface of the belt will be differently affected and caused to separate.

6. The combination, in a vanning-machine, of a swinging frame set level transversely and lower at one end than at the other, and an endless belt mounted on said frame, having its 35 upper part moving toward the higher end of said frame, with vibrating levers provided with fulcrums adjustable longitudinally as to said levers, and a cam adjustably connected 40 with the higher end of said frame to periodically cause it to rise gradually and drop suddenly through a greater or less distance, as may be desired, whereby the movements of 45 said frame and belt as to oscillation and as to rise and drop may be separately or jointly varied to adapt the machine to the separation of ores under various conditions, substantially as set forth.

7. The carrier-frame B, provided with the 50 drums E G, the intermediate rollers, g g, the belt D, carried and supported on said rollers, the guides H, and the sliding boxes i, fitted to said guides, combined with the screws h³ h³, which penetrate said boxes i, bevel-gears h² h², 55 attached to said screws, shaft i', and bevel-gears h' h' on shaft i' in mesh with bevel-gears h², whereby the two boxes i may be simultaneously moved to adjust the tension of the belt D.

60 8. The combination, in an ore concentrating or vanning machine, of a suspended swinging carrier-frame, B, drums E G, and traveling belt D, mounted thereon, with the belt wipers or scrapers x x, also carried by said frame, the driving-chains c² c² and their connecting-gearing, whereby motion is transmitted from 65 the wheel V on the main frame to the wipers

while the frame B is in motion, substantially as and for the purpose set forth.

9. The combination, in an ore concentrating 70 or vanning machine, of an oscillating and traveling belt, suitable drums to support said belt, and a swinging carrier-frame, B, with the vibrating arms R at their lower ends, jointed to said carrier-frame, adjustable pivotal slides R² for said arms, whereby the 75 length of vibration is regulated, the crank-rods n, and the driving-crank P, substantially as and for the purpose set forth.

10. The combination, in an ore concentrat- 80 ing or vanning machine, of oscillating frame B, belt D, adjustable vibrating arms R, rods n, cranks P, shaft l, cam N, fastened to and rotated by said shaft l, stirrups o, radial arm S, connecting-rod T, slide S', mounted in the radial arm S, made longitudinally adjustable, adjusting-screw s, and arms U, whereby the height to which the frame B is raised and dropped at each revolution of said cam N 85 may be adjusted, substantially as described. 90

11. The shaft u', arm S, and the arms U, attached thereto, combined with link-block S', fitted to slide longitudinally in said arm S, the screw s, mounted on said arm to move and hold said link-block, and the connecting-rod 95 T, jointed to said block, whereby with a uniform reciprocation of said connecting-rod the angular movement of the arm S may be varied at will.

12. The connecting-rod T, the arm S, link-block S', which is longitudinally adjustable in the arm S, and the adjusting-screw s for the 100 said block, combined with the bevel-wheel s² and bevel-wheel s' in mesh therewith, the chain-wheel t, and the chain t', whereby said 105 screw may be rotated at will to shift the adjustment of the link-block S'.

13. The connecting-rod T and the arm S, provided with a curved slot whose radius equals the length between centers of said connecting-rod, combined with a slide, S², fitted to slide in said slot, a link-block, S', a joint-pin, s⁴, penetrating said slide, and adapted to connect with said connecting-rod T, and the 110 adjusting-screw s, passing through said block 115 S', and in pivotal engagement with said arm S, whereby the position of the joint-pin s⁴ may be shifted without changing the angular position of said arm S.

14. In combination with the suspended 120 swinging frame B and its belt D, the vibrating levers R, jointed at their lower ends to said frame, the reciprocating connecting-rods n, combined with the pivot or fulcrum pins R², 125 longitudinally adjustable as to said levers R, whereby the relative lengths of the arms of 130 said levers may be varied, as and for the purpose set forth.

15. A swinging frame, B, its belt D, and a 130 vibrating lever, R, on each side of said frame, jointed thereto at their lower ends, and reciprocating connecting-rods, combined with adjustable pivot or fulcrum pins R², adjusting-screws R', for the same bevel-gears y, attached to said

screws, and the shaft y^2 , provided with bevel-gears y' in mesh with the bevel-gear y , whereby both of said pins R^2 may be coincidentally raised or lowered.

5 16. The traveling belt D, its frame B, and supporting-cords a' at the lower end, combined with the drums d , upon which said cords are wound, the sprocket e' , chain e^2 , the sprocket, ratchet, and pawl f^2 on shaft e^1 , and counter-
10 weight W', whereby the pitch of the frame B may be adjusted at will.

17. The combination, in an ore concentrat-

ing or vanning machine, of a reciprocating frame, B, traveling endless belt D, adjustable vibrating arms R, shaft l, cranks P, and cam 15 N, mounted thereon, crank-rods n, connecting-rod T, and radial arm S, whereby the lift of said frame is controlled, as set forth.
